UNITED STATES PATENT OFFICE.

HORACE H. TAYLOR, OF SAN JOSE, CALIFORNIA, ASSIGNOR OF ONE-HALF TO HIMSELF, AND ONE-HALF TO JOSEPH PEARSE, OF OAKLAND, CALIFORNIA.

TALKING-MACHINE.

No. 906,469.

Specification of Letters Patent.

Patented Dec. 8, 1908.

Application filed February 26, 1908. Serial No. 417,852.

To all whom it may concern:

Be it known that I, HORACE H. TAYLOR, a citizen of the United States, residing at San Jose, in the county of Santa Clara, State of California, have invented certain new and useful Improvements in Talking-Machines, of which the following is a specification, reference being had to the accompanying drawings.

10 My invention relates to talking machines, and has for its object to provide a new and improved construction by means of which the sound-box may be more easily and better applied to and lifted off from the record 15 upon which it rests, and by which the operator is enabled better to insert in the sound-box the usual needle. Heretofore it has been customary for the operator to take hold of the sound-box itself in these operations. While this has no bad effect if carefully and properly done, yet injury either to the fingers of the operator or to the instrument, or to both, very often occurs,—for example, when it becomes necessary to remove the sound-box quickly from the record to prevent injury to the instrument,—in which cases the needle sometimes causes painful or even dangerous injuries, or the mica diaphragm is broken or the sound-box otherwise injured or thrown out of adjustment.

25 The means I have provided for accomplishing the objects mentioned and for avoiding the difficulties heretofore experienced, are illustrated in the drawings and herein- 30 after specifically described.

35 That which I believe to be new will be pointed out in the claims.

In the drawings:—Figure 1 is a side elevation of a talking machine embodying one 40 form of my invention, the sound-box being shown in two different positions, one in dotted lines. Fig. 2 is an enlarged detail, showing a part only of the machine and illustrating the manner of applying the handle 45 or thumb-screw by which I am enabled to accomplish my purpose. Fig. 3 is an enlarged perspective view of the thumb-screw.

50 Referring to the several figures of the drawings, in which corresponding parts are indicated by like reference characters:—10

indicates a talking machine of the ordinary type, having applied to it the usual winding-key 11, and provided with the usual turn-table 12 and disk-record 13. From the rear rises an arm 14 carrying a collar 15 in 55 which is mounted so as to turn freely therein and to be supported thereby the ordinary horn 16. Also revolvably mounted in and supported by said collar 15 is a curved tube 17 at the free end of which is secured a 60 sleeve 18 adapted to form a bearing for a U-tube 19 one end of which is inserted in said sleeve. The other end of the U-tube 19 carries the usual sound-box 20. It is not believed that it is necessary to describe these 65 parts further here, inasmuch as they are well-known and form no part of my invention.

70 In the end of the U-tube which enters the sleeve 18 is secured a thumb-screw 21. As 75 will be readily understood, when it is desired to raise the sound-box from the record, this can be very effectually done by simply turning the thumb-screw 21, without any danger of injuring the fingers or the instrument no matter how hurriedly such operation may be done. In Fig. 1 I have shown in dotted lines the relative position of the parts thus moved when they are resting 80 on the record and also when raised from the record to apply a different record or to insert a new needle in the sound-box.

85 What I claim as my invention and desire to secure by Letters Patent is:—

1. In a talking machine, the combination 90 with a turn-table adapted to carry a record, a tube adapted to be swung on an axis perpendicular to the turn-table, a sleeve on the end of said tube, a U-tube one end of which is revolvably mounted in said sleeve, and a 95 sound-box mounted on the free end of said U-tube and adapted to rest on said record, of a handle secured to said U-tube and adapted to hold the same against withdrawal from said sleeve and by which said sound-box and U-tube may be lifted off from said record.

100 2. In a talking machine, the combination with a turn-table adapted to carry a record, a tube adapted to be swung on an axis per-

pendicular to the turn-table, a sleeve on the end of said tube, a U-tube one end of which is revolubly mounted in said sleeve, and a sound-box mounted on the free end of said 5 U-tube and adapted to rest on said record, of a thumb-screw secured so as to rotate therewith in the end of the U-tube which is mounted in said sleeve, whereby the U-tube

is held against withdrawal and by which said sound-box and U-tube may be lifted off 10 from the record.

HORACE H. TAYLOR.
